(57) **CLAIM**

The ornamental design for a stand, as shown and described.

DESCRIPTION

FIG. 1 is a right side elevational view of a stand for a cellular phone, tablet or the like, illustrating the new, original, and ornamental design;

FIG. 2 is a top plan view of the stand, illustrating the new, original, and ornamental design;

FIG. 3 is a bottom plan view of the stand, illustrating the new, original, and ornamental design;

FIG. 4 is a front elevational view of the stand, illustrating the new, original, and ornamental design;

FIG. 5 is a rear elevational view of the stand, illustrating the new, original, and ornamental design;

FIG. 6 is a top plan view of the stand in an unassembled state, illustrating the new, original, and ornamental design;

FIG. 7 is a perspective view of the stand from above the front, illustrating the new, original, and ornamental design;

FIG. 8 is a perspective view of the stand from the front, illustrating the new, original, and ornamental design;

FIG. 9 is a perspective view of the stand from the right side, illustrating the new, original, and ornamental design; and,

FIG. 10 is a perspective view of the stand from the right of the front, illustrating the new, original, and ornamental design.

The broken lines shown in the drawings are included for the purpose of illustrating environmental structure and form no part of the claimed design.
